UNITED STATES PATENT OFFICE

WILLIAM DENNIS, OF SHOREHAM, VERMONT

BRUSH

Application filed October 21, 1931. Serial No. 570,174.

This invention relates to a fountain brush and it consists in the novel features herein-after described and claimed.

An object of the invention is to provide a brush of simple and durable structure adapted to be used for applying a liquid to a surface.

The further object of the invention is to provide a fountain means for the brush adapted to contain the liquid, and having means whereby liquid may be ejected from the fountain as desired.

In the accompanying drawings:

Figure 1 is a side elevational view of the brush with parts broken away and parts shown in sections.

Figure 2 is a top plan view of the brush.

Figure 3 is a transverse sectional view of the brush cut on the line 3 3 of Figure 1.

The brush comprises a handle 1 having a plate 2 attached to the lower end thereof. Said plate is provided with an opening 3 which is normally closed by a cover 4. The

plate 2 is provided with a peripheral flange 5. A body 6 is attached to the flange and a ferrule 7 is mounted at the lower edge of the body 6. Bristles 8 are held in the lower portion of the body by the ferrule 7. The ferrule 7 is of rubber or other compressible material and serves as a dam to prevent the liquid from escaping at the outer side of the bunch of bristles. A partition wall 9 of rubber is disposed transversely across the lower portion of the body 6, and the said wall

30 9 is provided with a series of nipples 10 which lie between the upper portions of the bristles 8. The body 6 is adapted to retain a sponge 11 which sucks up the liquid poured into the body through the opening 3. A plate 12 is located in the body and may be moved to

35 compress the sponge 11 and squeeze the liquid therefrom, causing the same to flow through the nipples 10 into the bristles 8. A bolt 13 is slidably mounted in the side of the body 6 and the inner end of the bolt bears against the side of the plate 12. A knob 14 is carried at the outer end of the bolt 13.

A spring 15 surrounds the bolt 13 and bears 40 at one end against the knob 14 and at its other end against the side of the body 6.

When the finger is placed upon the knob 14 and the same is pressed so that the spring 15 compresses the inner end of the bolt 13 bearing upon the plate 12 moves the plate toward the sponge, squeezing the liquid from the same as hereinbefore described. When pressure is removed from the knob 14 the spring 15 returns the bolt 13 to normal position. As the brush is being used upon a surface, by grasping the handle 1 a liquid may be ejected 60 at desired intervals and applied to the surface over which the bristles pass.

Having described the invention, what is claimed is:

A brush comprising a reservoir body, a 65 partition wall of elastic material located in the body and having bristles on one side and nipples extending between the bristles, a sponge carried in the body, a movable plate located in the body and adapted to bear 70 against the sponge and a spring pressed pin slidably mounted in the side of the body and having an end bearing against said plate.

In testimony whereof I affix my signature.
